UNITED STATES PATENT OFFICE.

JONAS NORTHRUP, OF HOPEDALE, MASSACHUSETTS, ASSIGNOR TO WILLIAM F. DRAPER, OF HOPEDALE, MASSACHUSETTS.

PROTECTION MECHANISM FOR LOOMS.

No. 911,152.

Specification of Letters Patent.

Patented Feb. 2, 1909.

Application filed December 16, 1908. Serial No. 467,746.

To all whom it may concern:

Be it known that I, JONAS NORTHRUP, a citizen of the United States, residing at Hopedale, in the county of Worcester and State of Massachusetts, have invented an Improvement in Protection Mechanisms for Looms, of which the following description, in connection with the accompanying drawings, is a specification, like letters on the drawings representing like parts.

The invention to be hereinafter described relates to protection mechanism for looms for stopping the operation thereof when a shuttle fails to be boxed or is trapped in the shed. In mechanisms of this general character as heretofore employed a dagger has been carried by a dagger rod supported by the lay, and a finger connected to the dagger rod and moved by the binder, as the shuttle entered and left the shuttle box, has been raised and lowered on each round of lay movement.

In a prior application filed by me, Ser. No. 421,208, March 14, 1908, there is shown, described and claimed a protection mechanism and means for holding said mechanism in inoperative position during the entire lay movement when the shuttle is properly boxed, and movable into operative position only when a shuttle fails to be or is improperly boxed. The present invention is characterized generally by similar action, its object being to provide mechanism of this general nature which will be readily applicable to ordinary looms now in use.

In the drawings:—Figure 1 is a side elevation, showing sufficient portions of a loom to make clear the association of the present invention therewith, the lay and shuttle-box being shown in section; Fig. 2 is a plan view of one end of the lay and its shuttle-box and some adjacent parts, a shuttle being shown as properly boxed; Fig. 3 is a section on the line 3—3, Fig. 2, showing the adjustable pivotal mounting of a shuttle binder; and Fig. 4 is a detached perspective detail showing a form of shoe adapted to be detachably connected to the dagger.

The loom frame A, the lay 1, the front box-plate 2, cover-plate 3, and back-wall 4 of the shuttle-box, the shipper 5, knock-off lever 6, and the main portion of the frog 7 may be of any usual or desired construction.

Referring to Figs. 2 and 3, the lay beam 1 has extending therethrough the bolt 8 having

a head 9 preferably bearing on the top plate 3, and screw threaded at its opposite end to engage a nut 10, whereby the bolt 8 may act as a holding means for said top plate at its outer end, as indicated by Figs. 2 and 3. Interposed between the top plate 3 and the top of the lay beam is a sleeve 11 having projecting therefrom a bracket 12, said sleeve being formed with an opening 13 larger than the bolt and preferably elongated, as shown by Fig. 2. Pivotal mounted upon the sleeve 11 is the shuttle binder 14 which is normally pressed towards the shuttle-box by means of a spring, one end of which is seated against the binder at 16, and the other end of which is supported by a bearing head 17 formed on or carried by an adjusting screw 18 having a threaded engagement with a lug 19 on the bracket 12 and locked in adjusted position by a lock nut 20.

From the construction thus far described it will be apparent to one skilled in the art that upon loosening the nut 10 the bracket 12, and perforce the pivotal point of the binder 14, may be adjusted to vary the binder action upon the shuttle; and it will likewise be evident, since the bracket 12 carries the binder spring 15, that such adjustment does not of itself change the tensioned or adjusted condition of the binder spring 15, but that said binder spring may be separately and independently adjusted to suit conditions of use regardless of adjustment of the binder fulcrum.

Mounted in suitable brackets 21 carried by the lay 1 is the dagger rod 22, Figs. 1 and 2, having a dagger 23, and normally under the influence of a spring 24 tending to turn the dagger end downward or into operative position to engage the shoulder 25 on the frog 7 as the lay moves forward to "beat up". Projecting from the dagger rod 22 is an arm 26 having clamped thereto a binder finger 27 the upper end of which normally rests against the binder 14, as will be clearly apparent from the described structure.

Secured to the dagger in any desired or approved manner, as by the bolt and nut 28, is a shoe 29, the preferred detail character of which is indicated by Fig. 4, wherein the shoe is provided with an opening 30, adapted to receive the dagger 23, and an upwardly extending stop 31, adapted to contact with the lower portion of the lay beam to prevent undue rising movement of the dagger. The

shoe 29 has an opening 32 through which the bolt passes for securing the shoe to the dagger, the head of the bolt being preferably countersunk, as indicated in Fig. 1. Obviously the form and general character of the shoe 29 and its manner of attachment to the dagger may be greatly varied within the true scope of the present invention, as defined in the claims.

- 10 The frog 7 is provided with a riser 33 and a dwell or support 34, similar in character to like parts described in my prior application to which reference is made, and the said shoe 29 coöperates at times with these portions of 15 the frog as will now be described.

Assume that the lay is in position substantially as indicated by Fig. 1, and that a shuttle is being picked from one box to the other; at such time, the shoe 29 will rest upon the 20 dwell or support 34 and hold the dagger in its raised or inoperative position, and, as the lay moves forward, carrying the shoe 29 from the dwell or support 34, a shuttle having been properly boxed, the binder will hold 25 the finger 27 and consequently maintain the dagger in its raised or inoperative position. If, however, the shuttle fails to be or is improperly boxed, the binder will not be moved outward sufficiently to hold the 30 finger 27 and the dagger in its inoperative position, so that the dagger will respond to the demands of its spring and move downward into position to meet the shoulder 25 of the frog on the forward movement of the 35 lay, and stop the machine. Thus, when the loom is working under normal conditions and the shuttle is properly boxed on each pick, the dagger is maintained in substantially fixed inoperative position and has no 40 effective movement towards operative position, such movement to operative position occurring only when a shuttle fails to be or is improperly boxed.

It is to be noted that in the construction 45 above described the finger 27 extends into the path of movement of the binder, so that when the latter is moved outward by a properly boxed shuttle, it finds the finger 27 and holds it and consequently the connected 50 dagger from movement responsive to the spring 24 or other actuating means; and it will likewise be noted that the finger 27 contacts with the binder preferably at that end portion remote from its pivotal connection 55 with the lay, although in some forms of the invention this may not be essential. As will be evident, the pivotal mounting or fulcrum of the binder may be adjusted in the manner hereinbefore described, without materially 60 affecting the operative relation of the binder and parts co-acting therewith to stop the loom under the conditions described.

What is claimed is:

1. In a loom, the combination of a lay, a 65 dagger carried by the lay, a shuttle binder, a

finger connected to the dagger and extending into the path of movement of the binder as it is moved by a shuttle, and means including said binder and finger acting, when the shuttle is properly boxed, to maintain the dagger 70 in fixed inoperative position during the entire lay movement.

2. In a loom, protection mechanism including a dagger and means for normally holding said dagger from movement towards operative position during the entire cycle of lay movement, said means including a binder and a finger extending into the path of movement of the binder as it is moved by a shuttle, said means acting to permit operative 80 positioning of the dagger when the shuttle fails to properly box.

3. In a loom, protection mechanism including a dagger, means acting normally to move the dagger to operative position to stop 85 the loom, a shuttle binder, a finger connected to the dagger and extending into the path of movement of the binder as it is moved by a properly boxing shuttle, and means including said binder and finger to hold the dagger from movement towards operative position 90 throughout the cycle of lay movement when the shuttle is properly boxed.

4. In a loom, protection mechanism including a dagger, and means for normally holding said dagger from movement towards operative position throughout the cycle of lay movement when the shuttle is properly boxed, said means including a pivotally mounted binder and a finger extending into 100 the path of movement of the inner end portion of the binder as it is moved by a shuttle.

5. In a loom, the combination of a lay and its shuttle-box, a dagger carried by the lay, an adjustably mounted binder, a binder finger 105 connected to the dagger and positioned in the path of and to be met by the binder as it is moved by a properly boxing shuttle, and means including said binder and finger to maintain the dagger in inoperative position 110 throughout the cycle of lay movement when the shuttle is properly boxed.

6. In a loom, a lay, protection mechanism including a dagger, a frog having riser and dwell portions, and a shoe on said dagger having a stop to contact with the lay when the dagger is unduly raised.

7. In a loom, a lay, a dagger carried thereby, a frog having dwell and riser portions, a shoe on said dagger having a stop to contact 120 with the lay and prevent excessive upward movement of the dagger, a shuttle-binder, and a finger connected to the dagger and extending into the path of movement of the binder as the latter is moved by a properly 125 boxing shuttle.

8. In a loom, a lay and its shuttle-box, a binder, a bracket, a spring interposed between the bracket and binder, a dagger and connected finger to coöperate with the binder, 130

and means to simultaneously adjust the binder and bracket, the relation of the binder and finger remaining undisturbed by said adjustment.

5. 9. In a loom, a lay and its shuttle-box, a binder, a bracket, a spring interposed between the bracket and binder, a dagger and connected finger to coöperate with the binder, means normally tending to move the finger towards the binder, and means to simultaneously adjust the binder and bracket while maintaining the undisturbed relation of the binder and finger.
10. 10. In a loom, a lay and its shuttle-box, protection mechanism including a dagger, a binder pivotally mounted adjacent the outer

end of the shuttle-box, a finger connected to the dagger and positioned in the path of and to be met by the inner portion of the binder as the latter is moved by a properly boxing 20 shuttle, and means including said binder and finger to maintain the dagger from movement towards operative position during the entire cycle of lay movement when the shuttle is properly boxed.

In testimony whereof, I have signed my name to this specification, in the presence of two subscribing witnesses.

JONAS NORTHROP.
